BUFFING OR POLISHING WHEEL

Elisha W. Hall, Scituate, Mass.

Application January 29, 1937, Serial No. 122,925

4 Claims. (Cl. 51—193)

This invention relates to buffing or polishing wheels of the type in which the wheel comprises a plurality of sections, each composed of a plurality of plies of flexible fabric usually stitched together. In accordance with the present invention, the sections are joined together by adhesive at areas separated in a radial direction by areas not joined by adhesive and having a considerable degree of flexibility in a radial direction under the pressure of the work applied to the periphery of the wheel. Thus, although the wheel has a desirable firmness and the sections will not spread apart as in the case of sections wholly unattached, nevertheless the wheel possesses the requisite degree of resiliency in a radial direction under the pressure of the work. In other words, there is a cushion effect without undesirable, unlimited spreading of the sections, which characterizes a wheel in which the sections are wholly unattached. Each zone in which the sections are unattached is resiliently yieldable in and of itself, and this characteristic is preserved throughout the life of the wheel, because, as the wheel wears away there are still other alternating cemented and uncemented zones.

The invention will best be understood by reference to the following description when taken in connection with the accompanying drawings illustrating one specific embodiment thereof, while its scope will be pointed out more particularly in the appended claims.

In the drawings:

Fig. 1 is an elevation of a buffing or polishing wheel embodying the invention;

Fig. 2 is a sectional view on line 2—2 of Fig. 1 showing the wheel as it appears with no pressure applied to its periphery;

Fig. 3 is an elevation of one of the wheel sections with rings of adhesive applied thereto; and

Fig. 4 is a sectional view similar to Fig. 2, but illustrating the local yielding of the wheel in response to pressure applied in the direction of the arrow to the periphery of the wheel.

Referring to the drawings and to the embodiment of the invention illustrated therein by way of example, and having reference at first to Figs. 1 and 2, there is shown a buffing wheel comprising a plurality of sections each comprising a plurality of plies 8 of flexible fabric such as woven, cotton cloth whose thickness is greatly exaggerated, the plies shown being simply flat disks stitched together by threads 10, herein arranged, for example as shown in Fig. 1, gener-

ally in the form of a spiral. Each section is provided as usual with a central hole 12 to receive the usual shaft or spindle to which it is customary to secure the wheel by clamping plates and nuts.

The sections are prepared for assembly by coating them with an appropriate adhesive at areas separated in a radial direction by areas not joined by adhesive. In the present example, the coated areas are annular zones 14, 16 and 18 and they alternate with uncoated, annular zones 20, 22 and 24. The sections are then assembled face to face coaxially and the assembly is placed in a suitable press, preferably hydraulic, by which the wheel is subjected to tremendous pressure until the adhesive has set and the sections are thus strongly united. While glue may be used as the adhesive, best results are attained by the use of latex which is preferred because it does not become hard and brittle and does not score the work. Latex is also preferred because it retains a considerable degree of flexibility as compared with animal glue. When this flexibility and freedom from scoring of the work are not important, animal glue may be substituted.

The resulting wheel is characterized by the secure attachment of its sections together with freedom from relative rotation and from undue spreading of the sections under pressure of the work, combined with a desirable degree of resiliency, locally in a radial direction due to the fact that the unattached areas can flex with comparative freedom, as shown at the left-hand side of Fig. 4. It is difficult in a drawing to represent precisely how the flexing occurs in a rapidly rotating wheel, but it is characterized by local compression radially and corresponding lateral expansion or widening of the unattached areas, so that the effect at the periphery where the work is held is somewhat analogous to the local yielding of a pneumatic tire in contact with the ground.

Having thus described one embodiment of the invention but without limiting myself thereto, what I claim and desire by Letters Patent to secure is:

1. A buffing or polishing wheel comprising, in combination, a plurality of sections each comprising a plurality of plies of flexible sheet fabric stitched together, said sections being joined together by annular zones of flexible adhesive at areas separated in a radial direction by areas not joined by adhesive and having a considerable degree of flexibility in a radial direction under pressure applied to the periphery of the wheel.

2. A buffing or polishing wheel comprising, in combination, a plurality of sections each comprising a plurality of plies of flexible sheet fabric stitched together, said sections being joined together by flexible adhesive along annular zones separated by annular zones not joined by adhesive and having a considerable degree of flexibility in a radial direction under pressure applied to the periphery of the wheel.

3. A buffing or polishing wheel comprising, in combination, a plurality of sections each comprising a plurality of plies of flexible sheet fabric stitched together, said sections being joined together by latex at areas separated in a radial
- 10 10

direction by areas not joined by latex and having a considerable degree of flexibility in a radial direction under pressure applied to the periphery of the wheel.

4. A buffing or polishing wheel comprising, in combination, a plurality of sections each comprising a plurality of plies of flexible sheet fabric stitched together, said sections being joined together by latex along annular zones separated by annular zones not joined by latex and having a considerable degree of flexibility in a radial direction under pressure applied to the periphery of the wheel.
